COMBINED PORTABLE FILLING STATION BILLBOARD AND STORAGE TANK

Charles E. Knox, Jr., 1007 Slocum St., Dallas, Tex.

Filed Dec. 12, 1958, Ser. No. 53,755

Term of patent 14 years

(Cl. D13—1)

Fig.1

Fig.2

Fig.3

Fig.4

Fig.5

Figure 1 is a front elevational view of a combined portable filling station billboard and storage tank embodying my new design;

Figure 2 is a rear elevational view thereof;

Figure 3 is a top plan view thereof;

Figure 4 is a right side elevational view of the unit; and,

Figure 5 is a left side elevational view thereof.

The essential features of my design reside in the portion shown in full lines.

I claim:

The ornamental design for a combined portable filling station billboard and storage tank, substantially as shown and described.
